Patented Feb. 18, 1919.

FIG. 1

FIG. 2

FIG. 3

FIG. 4

Inventor
Philip F. Apfel
By Attorney
C. J. Hashim

UNITED STATES PATENT OFFICE.

PHILIP F. APPFEL, OF SEATTLE, WASHINGTON.

ELECTRIC HEATER.

1,294,597.

Specification of Letters Patent. Patented Feb. 18, 1919.

Application filed August 27, 1917. Serial No. 188,268.

To all whom it may concern:

Be it known that I, PHILIP F. APPFEL, citizen of the United States, residing at Seattle, in the county of King and State of Washington, have invented a certain new and useful Improvement in Electric Heaters, of which the following is a specification.

My invention relates to improvements in electric heaters of that class which are employed for igniting cigars, and the method of igniting said cigars, and the object of my invention is to provide an electric heater which shall be of such form of construction as will provide passageways for air there-through whereby the end of a cigar to be lighted may be disposed at the outlet end of said electric heater and the act of drawing air through the cigar will cause air to flow through said passageways wherein the air will be heated to a high temperature, by a heating conductor disposed within said electric heater, which heated air will quickly ignite the end of said cigar.

I accomplish this object by devices illustrated in the accompanying drawings, wherein—

Figure 1 is a view of my invention in front elevation;

Fig. 2 is a view in longitudinal mid-section on broken line 2, 2 of Fig. 1;

Fig. 3 is a view in cross-section on broken line 3, 3 of Fig. 2; and

Fig. 4 is a view in longitudinal mid-section showing a modified form of details of my invention.

Referring to the drawings, throughout which like reference numerals indicate like parts, a hollow body portion 5 of cylindrical form is made of refractory material that is a non-conductor of electricity, as porcelain or plaster of Paris, and embedded therein are two electrical conductors 6 and 7 which are disposed to extend from circuit connectors 8 and 9 (with which they are respectively connected) each to and through the back end wall 10 of the body portion 5.

The hollow heating element of cylindrical form, comprising the end portion 12, end portion 13, and the annular body portion 14, is made of refractory material that is a non-conductor of electricity, the inner space 15 of said heating element being flared at its end portion 12 to adapt it to guide the end of a cigar into the inner space 15.

Embedded within the circular walls of

the inner space 15, with a part of its surface exposed within the inner space 15, is an electrical heating conductor 16 whose ends 17 and 18 are extended to and through 60 the end portion 13.

Disposed to surround the heating element is a tube 19 which extends from the outer surface of the front end portion 12 to the outer surface of the end portion 13. 65

The end portion 12 of the heating element is provided with a plurality of holes, like holes 20, shown more clearly in Fig. 1, and the end portion 13 is provided with openings 21, shown more clearly in Fig. 3, 70 thereby forming a passageway for air from the exterior of said heating element through the holes 20, thence through the passageway 22, formed by the tube 19 and the body portion 14, thence through the openings 21 into 75 the recess 15.

The heating element including the metal tube 19 may be disposed snugly to fit within the inner space 11 of the body portion 5 whereby the ends 17 and 18 of the heating 80 conductor 16 will make contact with the circuit wires 6 and 7.

The construction of my invention as shown in Fig. 4 is similar to the construction shown in Figs. 1, 2 and 3 with the 85 exception of the winding of the heating conductor and the construction of the body portion of the heating element.

In Fig. 4, the electrical heating conductor 23, like the conductor 16 of Fig. 2, with 90 part of its surface exposed within the inner space 24, is embedded within the circular walls of the inner spaces 24 and is extended to and embedded within the annular body portion 25 with a part of its surface 95 exposed within the passageway 26 thereby forming a circuit extending from the outer surface of the heating element to and within the inner space 24 thereby affording a larger exposed surface of the conductor 23. 100

Disposed to extend through the body portions 25 are a plurality of holes 27 which form a passageway between the passageway 26 and the inner space 24.

The body portion together with the electrical element may be inclosed within any suitable casing, not shown, whereby it may be adapted for use to ignite cigars. 105

The heating elements including the conductors 16 and 23 may be made of any of 110 the different materials that are well known to those skilled in the art.

The operation of my invention as disclosed in Figs. 1, 2 and 3 is as follows: The circuit connectors 8 and 9 are connected by well known means to a source of electrical current, not shown, thereby causing a current of electricity to flow through the electrical heating conductor 16 whereby the conductor 16 is heated to a high temperature whereupon the end of a cigar is inserted into the inner space 15 and by drawing upon said cigar air will be caused to flow from the exterior of the heating element through the holes 20, thence through the passageway 22, thence through the openings 21 into the inner space 15 whereupon the air is heated to a high temperature and is drawn directly upon the end of the inserted cigar causing it to be ignited.

The operation of the device as disclosed in Fig. 4 is as follows: The circuit connectors are connected in a similar manner to the connectors 8 and 9 of Fig. 2 causing the heating conductor 23 to be heated to a high temperature whereupon the end of a cigar is inserted within the inner space 24 and by a drawing upon said cigar air will be caused to flow from the exterior of the heating element through the holes 20 thence through the passageway 26, where it is heated to a high temperature, part of which heated air being drawn through the holes 27 and part of which heated air being drawn through the openings 21, into

the inner space 24 where it is again heated to a still higher temperature within the inner space 24, from which inner space 24 the heated air is drawn directly upon the end of said cigar causing it to be ignited.

Obviously many changes may be made in the forms, dimensions and arrangement of parts of my invention without departing from the spirit thereof.

What I claim is:

An electric heater of the class described, which embodies a body portion, and an electric heating element disposed within said body portion, said heating element being provided with a passageway for air adjacent one end portion thereof, another passageway for air communicating with the first named passageway and extending to the rear end portion of said heating element and thence extending through the central portion of said heating element to the exterior thereof, said heating element also being provided with passageways for air extending from the second named passageway to the passageway extending through the central portion of said heating element whereby air may be heated during its passage through all of said passageways.

In witness whereof, I hereunto subscribe my name this 10th day of August A. D. 1917.

PHILIP F. APFEL.
